United States Patent Office.

E. R. WILLIAMS, OF ROCHESTER, NEW YORK

Letters Patent No. 81,856, dated September 1, 1868.

IMPROVED FRUIT-JAR.

The Schedule referred to in these Letters Patent and making part of the same.

TO ALL WHOM IT MAY CONCERN:

Be it known that I, E. R. WILLIAMS, of Rochester, in the county of Monroe, and State of New York, have invented a certain new and useful Improvement in Fruit-Jars; and I do hereby declare that the following is a full and exact description thereof, reference being had to the accompanying drawings, making part of this specification, in which—

Figure 1 is a section of a jar with my improved stopper.

Figure 2, a perspective view of the stopper.

Like letters of reference indicate corresponding parts in both figures.

My invention consists in the special form and arrangement of the stopper, which is made grooved on one side and inclined on the other, and which packs in the mouth of the jar by means of an elastic strap, as hereinafter set forth.

In the accompanying drawings, A indicates the jar, and B the stopper, which is preferably made of glass. On one side of the stopper is formed a groove or concavity, *a*, which extends around about one-third of its circumference, and graduates into an incline, *b*, as shown. The stopper B is provided with the usual packing, *d*.

On one side of the stopper is formed a lug, *g*, corresponding in position with lug *h* on the neck of the jar. Over these lugs is hooked an elastic band, *i*, of India rubber, which serves to hold the stopper in place when it is inserted in the mouth *p* of the jar, which is done by first inserting the grooved side, and then pressing down the incline, thereby hooking the stopper in place.

By means of the groove *a* of the stopper fitting over the neck *p*, the stopper itself is made self-retaining on one side, while on the opposite side the elastic band *i*, hooking over lugs *g* *h*, serves to secure the stopper in place.

Much difficulty has been experienced from the pressure of the gas that collects from the fruit inside the jar, and sometimes the pressure is so great as to force the cover off altogether, and expose the fruit. In my device, when the pressure of the gas is sufficient to overcome the atmospheric pressure outside, the elasticity of the band *i* will yield enough for the stopper to rise and allow the gas to escape, the grooved side acting as a sort of hinge.

This construction is exceedingly cheap, and the packing and locking in place are accomplished in the simplest manner. These advantages are obvious at first glance.

What I claim as my invention, and desire to secure by Letters Patent, is—

The construction of the stopper B, with a groove, *a*, extending part way around, and graduating into an incline, *b*, when employed in connection with the elastic band *i*, in the manner and for the purpose specified.

In witness whereof, I have hereunto signed my name in the presence of two subscribing witnesses.
